Fig. 2

Des. 197,997

PAGE 3

Fig.3

Fig. 4

FIG. 1 is a front perspective view of a printing machine embodying my new design;

FIG. 2 is a right side perspective view thereof;

FIG. 3 is a rear perspective view; and

FIG. 4 is a left side perspective view thereof.

The dominant features of the design reside in those portions shown in full lines.

I claim:

The ornamental design for a printing machine, substantially as shown and described.
